UNITED STATES PATENT OFFICE.

EDWARD G. THOMAS, OF SPRINGFIELD, ILLINOIS.

CHILD'S PLAY-TABLE.

1,377,860.

Specification of Letters Patent. Patented May 10, 1921.

Application filed March 31, 1917. Serial No. 159,004.

To all whom it may concern:

Be it known that I, EDWARD G. THOMAS, of Springfield, county of Sangamon, State of Illinois, have invented and produced certain new and useful Improvements in a Child's Play-Table, of which the following is a specification, reference being had to the accompanying drawings, which form a part thereof.

10 Specification.

My invention consists of a removable apron for a baby's chair or buggy which will serve for a play table of area sufficient 15 to prevent the dropping of toys or food upon the floor. At a certain age the tendency of a child to drop its toys to the floor becomes annoying since the constant presence of an attendant is necessary to keep the 20 child supplied with something to divert its attention. My play-table provides a means for retaining the toys within the child's reach and can be readily removed and folded up into a small space.

25 The invention is illustrated by the drawings which accompany and form a part of this specification. Figure 1 is a view in isometric perspective of the device attached to an ordinary child's high chair. Figs. 2, 30 3, 4 and 6 show modifications of certain parts and Fig. 5 illustrates details of construction.

The device consists, in Fig. 1, of four arms 1, 2, 3, and 4 removably supported in 35 brackets 5 fastened to the seat 24 of a chair 7. An apron 8 of fabric, leather or other flexible material is supported by the arms 1, 2, 3 and 4 so as to cover the included space, an opening 9 being cut out to permit the 40 apron to extend more or less around the child's body. A belt 10 is sewn to the edge of the apron around opening 9 and is provided with straps 11 and 12 to be tied around the child's body and straps 13 and 45 14 by which it may be secured to the chair, thus forming a safety belt.

Apron 8 may be secured to arms 1, 2, 3 and 4, by inserting the ends of the arms into 50 pockets 15 at its corners as is shown in Fig. 3, which represents the apron turned over and showing its lower side. A preferable construction is shown in Fig. 1, where spreader rods 16, 17 and 18, to which the apron 8 is secured, extend between the ends 55 of arms 1, 2, 3 and 4, and are supported

thereby in a manner to permit ready attachment and removal. A convenient construction will be to provide holes in the spreaders at suitable points through which the ends of arms 1, 2, 3 and 4 may pass as is illustrated 60 in Fig. 5, where a collar 19 on the arm furnishes a surface on which the spreader may rest.

The height of the spreader bars will preferably be slightly greater than the child's 65 waist and the apron will then sag somewhat toward the child, causing objects dropped upon it to tend to roll toward the child, and thus remain within easy reach.

In order to insure the appropriate location of the removable arms, they may be secured in the brackets by set screws 20 as is shown in Fig. 1, or they may be of rectangular section and fit into holes 23 of similar contour in the brackets, as illustrated in 75 Fig. 2.

The spreader bars 16, 17 and 18 are pivotally joined by bolts 21 and 22 and when removed from the supporting arms may be folded together and rolled in the apron so as 80 to occupy very little space when not in use.

Other constructions are shown in Fig. 6, where the spreader rods are joined when in use by placing both of the rods which come together, over the upturned end of a supporting arm, and in Fig. 4, where the arm 2 and the spreader rods 17 and 18 are formed with eyes 25, 26 and 27 which engage one 85 another, whereby the entire support of the apron 8 is joined into a unit structure which 90 will fold into a small space.

The flexible surface afforded by the cloth is especially desirable in avoiding the destruction of toys by the pounding of the child and in fitting the child's body so as to 95 prevent anything from being dropped between the apron and the child.

This play-table may be modified in many structural respects without thereby departing from my invention. As such modifications will readily occur to those skilled in mechanic arts I have not deemed it necessary to illustrate them here.

Claims.

1. In a child's play-table, the combination of means for supporting a child in a sitting position, brackets secured to the seat thereof, a pair of upwardly and divergently extending arms removably supported by said brackets on each side of said seat, and 105

110

a flexible apron supported by said arms above the level of said seat.

2. In a child's play-table the combination of a means for supporting the child in a sitting position, brackets secured thereto at the level of the seat thereof, upwardly-extending arms supported thereby, a flexible apron attached to said arms, and means for fastening said apron to the body of the child and 10 to its means of support.

3. In a child's play-table the combination of means for supporting a child in a sitting position, brackets attached thereto, arms supported by said brackets, means for securing said arms in definite angular locations relative to said brackets and a flexible apron supported by said arms.

4. In a child's play-table the combination of means for supporting a child in a sitting 20 position, brackets secured thereto at the level of the seat thereof, a flexible apron adapted to be attached to the child and a foldable unit structure for supporting the outer edge of the apron and adapted to engage said brackets.

5. In a child's play table the combination of a means for supporting a child in a sitting position, brackets secured thereto at the level of the seat thereof, upwardly-extending supports removably attached thereto and extending outwardly therefrom, a U-shaped frame consisting of members foldably joined together and a flexible apron stretched between the members of said frame.

35 6. In a child's play table the combination of a means for supporting a child, a frame constituting three sides of a rectangle and consisting of members foldably joined at the

corners of the rectangle, braces extending upwardly and outwardly from said means 40 and foldably united to the members of said frame at the corners thereof and a flexible apron supported by said frame.

7. In a child's play table the combination of means for supporting a child in a sitting 45 position, brackets attached thereto, sockets in said brackets, arms adapted to fit in said sockets and to be upheld thereby, and a flexible apron supported by said arms.

8. In a child's play table the combination of means for supporting a child in a sitting position, brackets attached thereto, sockets in said brackets arms adapted to fit in said sockets and be upheld thereby, means for preventing motion of said arms in said 55 sockets and a flexible apron supported by said arms.

9. In combination a child's chair having a seat, a pair of upwardly and divergently extending arms attached to each side of the 60 seat thereof and a flexible apron supported upon the outer ends of said arms.

10. In combination a child's chair, a rectangular flexible apron and upwardly and divergently extending arms attached to the 65 seat of said chair adapted to engage said apron at the corners thereof and support it above the level of said seat.

In testimony whereof I have signed my name to this specification in the presence of 70 two subscribing witnesses.

EDWARD G. THOMAS.
